Primary Examiner — Manpreet Matharu*Assistant Examiner* — Suzanne Tisdell*(74) Attorney, Agent, or Firm* — Clement Cheng(57) **CLAIM**

The ornamental design for a battery housing, as shown and described.

DESCRIPTION

FIG. 1 is a perspective view.

FIG. 2 is a front view.

FIG. 3 is a rear view.

FIG. 4 is a left side view.

FIG. 5 is a right side view.

FIG. 6 is a top view; and,

FIG. 7 is a bottom view.

The broken lines in the drawings depict portions of the battery which form no part of the claimed design.

1 Claim, 3 Drawing Sheets(56)
